UNITED STATES PATENT OFFICE.

PERCIPHOR B. SNEATH, OF PHILADELPHIA, PENNSYLVANIA, ASSIGNOR OF ONE-HALF TO LEONARD ZEISER, OF SAME PLACE.

GRATE FOR RANGES, &c.

SPECIFICATION forming part of Letters Patent No. 642,378, dated January 30, 1900.

Application filed August 22, 1899. Serial No. 728,056. (No model.)

To all whom it may concern:

Be it known that I, PERCIPHOR B. SNEATH, of Philadelphia, in the State of Pennsylvania, have invented certain new and useful Improvements in Grates for Ranges, &c., whereof the following is a specification, reference being had to the accompanying drawings.

My invention belongs to that class of grates in which the grate-bars are arranged to be vibrated or shaken in order to facilitate the discharge of ashes; and the object of my present improvements is to obtain a simple and inexpensive construction possessing great strength and easily operated in performing the functions required.

Referring to the drawings, Figure 1 represents a plan view of my improved grate. Fig. 2 is a transverse vertical section on the line 2 2, Fig. 1. Fig. 3 is a central longitudinal section. Fig. 4 is a detail view in perspective, showing a portion of one grate-frame.

The general construction of the range or furnace is not indicated in the drawings; but it is such as to embody a rectangular frame A, having deep end pieces A' A² and side pieces a a' of less vertical depth. This constitutes the housing or support of the grate proper. Running longitudinally through said frame is a rock-shaft B, mounted in suitable bearings in the end pieces A' A² and arranged slightly to one side of the longitudinal central line of the frame. Said shaft has a squared end b, adapted to receive an ordinary handle or winch, whereby it may be rocked or turned, as desired, and has also four squared portions M M' N N', whose purpose will be hereinafter described. Beneath the side pieces a a' of the frame A are two rectangular grate-frames C D, the outer grate-frame C having transverse grate-bars C' and inclosing the inner grate-frame D, which has transverse grate-bars D'. The sides of said inner grate-frame D are suitably notched, as indicated at E, so as to receive the transverse grate-bars C' of the outer frame. The depth of these notches is such that the tops of the bars C' are flush with the upper surface of the inner grate-frame D, and thus the bars of both grate-frames lie in the same horizontal plane. The two grate-frames C and D are thus capable of reciprocation relatively to one another in a direction parallel to their grate-bars. The

bars C' are provided with raised projections C of angular form, and the bars D' have similar projections d, arranged at alternating intervals with the other projections.

On the top of the sides of the outer grate-frame C are mounted inwardly-projecting fingers F, which closely overhang the inner grate-frame D for a short distance, said projecting fingers being arranged in line with the bars D' of the inner grate-frame and being of such vertical height as to slide freely beneath the sides a a' of the frame A.

The end pieces of the grate-frame C are formed with downward extensions G G', respectively, having elongated transverse slots g g'. The grate-frame D has similar downward projections H H', similarly slotted at h h', the respective pairs of slots registering with one another, so that the rock-shaft B passes through the slots at the ends of both grate-frames and supports said frames, while allowing a lateral play thereof with relation to said rock-shaft. The inner faces of the said end pieces of the outer grate-frame C are provided near the top with inwardly-projecting lugs K K' and K² K³, arranged in pairs, whose members face one another with a short interval between. The outer faces of the end pieces of the grate-frame D are provided near the bottom of the extensions H H' with similar pairs of lugs L L'. Said end pieces of the inner grate-frame D have slots e e' (see Fig. 4) extending vertically downward from the center of the elongated slots h h', the width of said slots being slightly larger than the diameter of the rock-shaft B.

The rock-shaft B has, as before stated, four squared portions M M' N N', situated as follows: The squared portion M is intermediate between the front end piece A' and the proximate face of the end piece of the grate-frame C. The next squared portion M' is between the inner face of the said end piece of the grate-frame C and the proximate face of the front end piece of the grate-frame D. At the other end of the shaft the squared portion N is between the outer face of the rear end piece of the grate-frame D and the inner face of the rear end piece of the outer grate-frame C, and the squared portion N' is between the outer face of the rear end piece of the grate-frame C and the inner face of the rear end

piece A² of the frame A. The squared portions M' and N engage operatively with correspondingly - squared openings in yoke-shaped lever-pieces P R, respectively. The 5 upper arm of the lever-piece P engages between the lugs K K' of the outer grate-frame C, and the lower arm of said lever engages between the lugs L L' of the inner grate-frame D. The upper arm of the lever-pieces R engages between the lugs K² K³ of the outer 10 grate-frame, and the lower arm of said lever engages between the lugs L' upon the rear of the inner grate-frame D.

A removable pin or stop S is mounted in 15 the front end piece A' and extends inwardly beneath the front end piece of the grate-frame C, so as to afford a rest therefor at one side. As before stated, the rock-shaft B does not run on the central longitudinal axis of the 20 frame A, but is arranged slightly to one side thereof, and the stop S is placed toward the side a of the frame A which is nearest to the rock-shaft B. When said stop is removed, the grate-frames C D are free to oscillate together 25 with relation to the frame A in a direction indicated by the arrow in Fig. 2, such rotation being effected by merely turning the rock-shaft B in the proper direction. The squared portions M and N' upon said rock- 30 shaft serve as distance-pieces to maintain the proper relation between the ends of the outer frame A and the grate-frame C.

The operation of the device is as follows: When it is desired to rake the fire, the handle 35 is applied to the squared end b of the rock-shaft B and the latter is oscillated backward and forward. The grate-frames are thus caused to reciprocate horizontally in opposite directions, and the projections upon 40 the top thereof (together with the finger-pieces which extend over the grate-bars upon the frame D) thoroughly disintegrate the ashes and clinker, so that it is discharged at the bottom. The finger-pieces also tend to 45 prevent any large lumps of ashes or coal from getting in between the side pieces of the grate-frames, and thus obviate the danger of jamming. When it is desired to dump the 50 contents of the grate, the pin S is shifted outwardly from beneath the frame C and the entire grate revolved by turning the shaft B around until the grate-frame stands vertical, or nearly so. As the longer ends of the grate-bars are on the side opposite to that which is

supported by the pin S, the grate structure as 55 a whole is slightly overbalanced on the side opposite to the pin S, and hence little or no strain is occasioned upon the pin.

The above-mentioned parts can readily be 60 cast and made interchangeable, so that a very cheap structure is afforded, and the parts can be renewed as they become worn.

Having thus described my invention, I claim—

1. The combination, with a supporting-frame, of a pair of grate-frame adapted to reciprocate with relation to each other; a rock-shaft supporting said grate-frames and engaging in elongated slots therein; a lever mounted upon said rock-shaft; and lugs upon 70 said grate-frames arranged in the described relation to said lever, whereby oscillation of the rock-shaft is permitted to effect the reciprocation of said frames relatively to each other, substantially as set forth.

2. The combination, with a supporting-frame, of a pair of grate-frames adapted to reciprocate with relation to each other; a rock-shaft supporting said grate-frames and engaging in elongated slots therein; a lever 80 mounted upon said rock-shaft; lugs upon said grate-frames arranged in the described relation to said lever, whereby oscillation of the rock-shaft is permitted to effect the reciprocation of said frames relatively to each 85 other; and a pin mounted in said inclosing frame and projecting beneath one of said grate-frames, substantially as set forth.

3. The combination, with a supporting-frame, of an inner grate-frame having slotted 90 sides; an outer grate-frame inclosing said inner grate-frame, the grate-bars of said outer grate-frame being arranged to slide freely in the slots of the inner grate-frame; a rock-shaft extending longitudinally through said 95 frame and arranged in elongated slots in the inner and outer grate-frames, said rock-shaft having a portion of its surface squared; a rocking-lever detachably mounted upon the squared portion of the rock-shaft and engaging 100 said grate-frames; and a pin mounted in the outer frame and adapted to engage beneath one of said grate-frames, substantially as set forth.

P. B. SNEATH.
